UNITED STATES PATENT OFFICE.

ALBERT J. HITCH, OF RIDGETOWN, ONTARIO, CANADA.

RAILWAY SIGNALING APPARATUS.

No. 838,542.

Specification of Letters Patent.

Patented Dec. 18, 1906.

Application filed December 4, 1905. Serial No. 290,113.

To all whom it may concern:

Be it known that I, ALBERT J. HITCH, a subject of the King of Great Britain, residing at Ridgetown, county of Kent, in the Province of Ontario, Canada, have invented certain new and useful Improvements in Railway Signaling Apparatus; and I do hereby declare that the following is a full, clear, and exact description of the invention, such as will enable others skilled in the art to which it appertains to make and use the same.

My invention relates to railway signaling apparatus.

The object of my invention is to provide means for indicating at a central point—say a train-despatcher's office—the location of trains passing over a line and for indicating the open and closed positions of switches at the train-despatcher's office.

A further object of my invention is to provide means for indicating to the driver of an engine the approach of another train, which latter indicating means are operable from the train-despatcher's office; and my invention consists of the construction, combination, and arrangement of parts, as herein illustrated, described, and claimed.

In the accompanying drawings, forming part of this application, I have illustrated one form of embodiment of my invention, in which drawings similar reference characters designate corresponding parts, and in which—

Figure 1 is a diagrammatic view showing the arrangement of electrical circuits adapted to operate my invention. Fig. 2 is a rear elevation, partly in section, of a locomotive, showing the arrangement of the means adapted to indicate to an engine-driver the approach of a train. Fig. 3 is a side elevation of the rear portion of an engine, showing the application of the means adapted to indicate to the engine-driver the approach of the train. Fig. 4 is a front elevation of an indicating apparatus, the front wall of the casing of which is removed and the indicating members shown in one position. Fig. 5 is a front elevation of the indicating device, the indicating members being shown in a position different to that of Fig. 4. Fig. 6 is a vertical section through the indicating device shown in Fig. 4, and Fig. 7 is a longitudinal section through a contacting device adapted to be operated by the flanges of the wheels of railway-trains.

Referring to the drawings, 1 designates a casing placed at a central point—say in the

despatcher's office—and provided with a plurality of openings 2. Disposed within the casing are a plurality of brackets 3. Disposed adjacent the brackets are a plurality of levers 4, pivoted to the brackets, as at 5, Fig. 6. Connected to one end of each of the levers 4 is a link 6, carrying on its end a tablet 7, bearing the inscription "Off," adapted to fill the opening 4 adjacent thereto.

Secured within the casing 1 are a plurality of stops 8, adapted to limit the movement of the levers 4. Disposed on the rear wall of the casing are a plurality of tablets 9, arranged opposite to the openings 2 and adapted to be seen through said openings when the levers 4 are rocked, so that the tablets 7 do not cover said openings.

Secured to the ends of the levers 4 are springs 10, adapted to normally elevate the tablets 7 so as to cover the openings 2. Disposed beneath the levers 4 are magnets 11, having their armatures 12 connected to the levers and adapted to overcome the tension of the springs 10 and depress the levers 4, so that the tablets 7 are withdrawn from over the openings 2, so that the tablets 9 can be seen. The magnets 11 are placed in electrical connection with a suitable source of electricity, as the battery 13, suitable wires 14 being used for that purpose.

The wires 14 are led into casings 15, placed at various stations along the railway-line or at other suitable intervals. These casings 15, Fig. 7, are supported upon suitable springs 16, which bear on plates 17, and the casings and the plates are connected by bolts 18, the plates 17 being secured to the ties. Disposed on the lower casings 15 are upper casings 19, and both casings 15 and 19 are provided with binding-posts 20, adapted to receive the ends of the wires 14.

Disposed between the casings 15 and 19 are helical springs 21, held in place by screw-threaded rods 22, the upper ends of which are adapted to thrust into the collars 23, formed on the under surface of the upper casings 19, when the upper casings are depressed by the flanges of the wheels of a locomotive or car. The length of the casings 19 corresponds to the distance between the centers of the wheels of a locomotive or car truck, so that as a train passes over the casing it will be depressed by said wheels.

The casing 19 being depressed, the binding-posts 20 contact to close the circuit through the wires 14, thereby energizing the magnet

11 in that circuit and attracting the armature 12, so that the corresponding tablet 7 is withdrawn, and the tablet 9 opposite to that tablet may be viewed through the corresponding opening 2.

5 The disposition of the stations A B C D, &c., on the casing 1 will correspond to the disposition of the casings 19, so that when a train passes over any particular casing 19 it 10 will be indicated on the corresponding indicator on the casing 1 and will indicate at the despatcher's office that a train is passing that particular station, thus obviating the necessity of a telegraph operator at a station where 15 no train orders are delivered.

The casing 1 is provided with a switch-indicator 24, of similar construction to the station-indicators already described, in connection with the battery 13 by means of the 20 wires 25, the tablet 9 in this case being provided with the word "Open" and the tablet 7 being provided with the word "Shut," so that the train-despatcher will be advised of the opening and closing of a switch. The 25 circuit in this case is closed by means of the contacts 25^a, Fig. 1.

The sidings of the railway-line will be provided with indicators 26, similar in construction to the station-indicators, suitable wires 30 27 being in connection with the battery 13 and the circuit being closed by the mechanism already described for the stations, the only difference being that the tablets 9 are provided with the word "Clear" and the tablets 7 with the words "Not clear" or similar 35 words.

A switch 28 is placed on the casing 1, adapted to break the circuit formed by the wires 28^a, which wires are supported in any 40 suitable way adjacent the railway-tracks. The cab 31 of the locomotive is provided with a bell 29 and a light 30. The engine 35 is further provided with hangers 32, adapted to make a connection with the wires 28^a by 45 means of the trolley-wheels 34, which trolley-wheels are in electrical connection with the bell and light by means of the wires 33. This construction may also be placed in a coach, where it may be seen or heard by the 50 conductor of the train.

When in the train-despatcher's office it appears that two trains are approaching each other, the switch 28 may be thrown to make the circuit through the wires 28^a, and by 55 means of this electrical circuit the bell 29 will be rung and the light 30 will be lighted, thus notifying the engineer and conductor that a train is approaching. The circuit formed by the wires 28^a will be divided into 60 sections, so that one section will be independent of the other along the railway-line, so that in case of accident or breakage of one section it will not interfere with the operation of the other circuits.

Disposed on the casing 1 adjacent the 65 switch 28 in the circuit formed by the wires 28^a is a light 35. When the circuit is made by the switch 28, the light 35 will be lighted. In case of an accident in which the wires 28^a are broken the circuit will not be completed 70 by the switch 28, so that the light 35 will not be lighted, thereby indicating to the despatcher that there has been an accident and this circuit is not complete.

The casing 1 is provided with the representation 36 of the track corresponding to the location of the stations A B, &c., and the switches and sidings on the line of railroad.

Having thus fully described my invention, what I claim as new, and desire to secure by 80 Letters Patent, is—

1. In a railway signaling apparatus, a casing provided with openings therein, fixed indicators adapted to be viewed through the openings, movable indicators adapted to 85 cover the openings, resilient means adapted to normally maintain the movable indicators over the openings and electrically-operated means for moving the movable indicators.

2. In a railway signaling apparatus, a casing provided with openings therein, fixed indicators within the casing, movable indicators disposed within the casing, links connected to the movable indicators, levers connected to the links, resilient means for maintaining the movable indicators in elevated 95 position, and means operated by the passage of a train and adapted to actuate the movable indicators to a lower position.

3. In a railway signaling apparatus, a casing, fixed indicators within the casing, movable indicators adapted to cover the fixed indicators, levers connected with the movable indicators, brackets within the casing, adapted to pivotally support the levers, springs 105 adapted to normally elevate the movable indicators, means for overcoming the tension of the springs operated by the passage of a train, and means for limiting the movement of the levers.

4. In a railway signaling apparatus, a casing, fixed indicators disposed within the casing, movable indicators adapted to cover the fixed indicators, levers adapted to support the movable indicators, resilient means normally maintaining the movable indicators in one position, means operated by the passage of a train adapted to actuate the levers to another position, and brackets within the casing adapted to limit the movement of the levers.

5. In a railway signaling apparatus, a casing, indicating members in the casing, resilient means for maintaining one of the indicators in one position, means for moving one of said indicators, electrical connections to said means, casings adapted to receive the ends of said electrical connections, means for resili-

ently supporting the ends of the casings, and means for maintaining the ends of said connections out of contact with each other.

6. In a railway signaling apparatus, indicating members, electrical means adapted to move some of said indicating members, wires forming a circuit to said electrical actuating means, a lower casing adapted to receive the end of one of said wires, resilient means for supporting said casing, an upper casing disposed on the lower casing and adapted to receive the other of said wires, and springs disposed between said upper and lower casings adapted to normally maintain the ends of said wires apart.

7. In a railway signaling apparatus, indicating members, electrical means adapted to move some of said indicating members, wires forming a circuit to said electrical actuating means, a lower casing adapted to receive the end of one of said wires, an upper casing disposed on the lower casing and adapted to receive the other of said wires, resilient means for supporting the lower casing, springs disposed between said upper and lower casing adapted to normally maintain the ends of said wires apart, and a resilient support for said lower casing.

8. In a railway signaling apparatus, indicating means, electrical means for operating said indicating means, which electrical means are disposed in electrical circuits nor-

mally open, and means for maintaining the ends of said circuits apart comprising a lower casing provided with binding-posts, springs disposed on the ends of said lower casing, plates adapted to receive the thrust of said springs, bolts connecting said plates and said casing, an upper casing disposed on the lower casing, and provided with collars on its under surface, binding-posts carried by the upper casing, screw-threaded rods carried by the lower casing, and helical springs disposed on said screw-threaded rods.

9. In a railway signaling apparatus, the combination comprising a casing having the names of stations thereon, and having thereon the representation of the track on which the stations are situated, fixed indicating members adjacent the names of the stations, movable indicating members, and means adapted to be actuated by the passage of a train for moving the movable indicating members to cover the fixed indicating members and to indicate on the casing the position of a train on the tracks with relation to the station-names.

In witness whereof I have hereunto set my hand in the presence of two witnesses.

ALBERT J. HITCH.
